United States Patent Office

Des. 225,145

Patented Nov. 21, 1972

225,145

LOVESEAT

Thomas Winrow, Naperville, Ill., assignor to Futorian Corporation, Amsterdam, N.Y.

Filed Nov. 30, 1970, Ser. No. 26,207

Term of patent 14 years

The portion of the term of the patent subsequent to July 19, 1985, has been disclaimed

Int. Cl. D6—02

U.S. Cl. D6—63

The figure is a perspective view of a loveseat illustrating my new design. The back of the loveseat is conventionally plain while the side not shown is substantially identical to the side shown.

I claim:

The ornamental design for a loveseat, substantially as shown and described
